ATTORNEY

UNITED STATES PATENT OFFICE.

HUGH A. ROBINSON, OF KEYPORT, NEW JERSEY, ASSIGNOR TO AEROMARINE PLANE & MOTOR CO., INC., A CORPORATION OF NEW YORK.

AEROPLANE.

1,345,885.

Specification of Letters Patent.

Patented July 6, 1920.

Application filed August 23, 1918. Serial No. 251,071.

To all whom it may concern:

Be it known that I, HUGH A. ROBINSON, a citizen of the United States, residing at Keyport, in the county of Monmouth and State of New Jersey, have invented certain new and useful Improvements in Aeroplanes, of which the following is a specification, reference being had therein to the accompanying drawing.

My invention relates to improvements in aeroplanes and more particularly has reference to a metal tail post, rudder lock and saddle stay.

Referring to the accompanying drawings, I have illustrated in Figure 1 in perspective parts being broken away, a suitable form of tail post embodying an application of my invention. Fig. 2 is a view looking from left to right at Fig. 1. Fig. 3 illustrates a detail of one of the connecting parts and Fig. 4 is a cross-section on the line 4—4 of Fig. 2.

5, 6, 7 and 8 indicate the longerons which it will be observed are socketed in the upper and lower portions of the tail post 10 and are held in position by suitable bolts such as 9. 11 indicates other bolts upon which the fittings 12 shown in Fig. 3 may be secured for anchoring the turnbuckles such as 13. The tail post may be cut away in various places as indicated by the reference character 14 for lightness if desired and to allow for the escape of air, and may also be provided with holes such as 15 for securing the covering 15 of cloth or other material. 16 indicates the rudder lock or support for the rudder which is preferably secured to the back of the tail post as shown in Fig. 2 and may be held by a nut such as 16' if desired, a lug, or projection such as 17 being adapted to engage a hole such as 18 in the back of the tail post to prevent the same from turning.

This construction it will be observed provides a strong and rigid anchorage and support for the various parts without involving 45 too much weight, while at the same time allowing for the escape of air and for securing the cloth or other covering of the fuselage.

Of course, it will be understood that various modifications may be made in the construction and arrangement of parts without departing from the spirit of the invention as claimed.

I claim:

1. In a device of the class described, a three sided metallic structure having upper and lower sockets within which may be secured the longerons of an aeroplane and rudder locks at the back thereof within 60 which may be supported a rudder.

2. In a device of the class described, a three sided metallic structure having upper and lower sockets within which may be secured the longerons of an aeroplane and 65 rudder locks at the back thereof within which may be supported a rudder and in combination therewith means for securing guy wires within said device.

3. In a device of the class described, a 70 three sided metallic structure having upper and lower sockets within which may be secured the longerons of an aeroplane and rudder locks at the back thereof within 75 which may be supported a rudder, the sides of said device tapering outwardly in the direction of the open side.

In testimony whereof I hereunto affix my signature in the presence of two witnesses.

HUGH A. ROBINSON.

Witnesses:

DAVID H. DOUGLASS,
THOMAS A. HILL.
